MOTOR FUEL PROCESS

Application filed October 24, 1928. Serial No. 314,631.

The present invention relates to an improved method for refining crude coke oven light oil obtained by the destructive distillation of coal and particularly to an improved method for the production from such oil of a motor fuel adapted for use in internal combustion engines, and to the improved fuel thus produced.

In the production of motor fuel from light oil as carried out heretofore, it has been the practice to submit the oil or the particular fraction thereof which is useful as a motor fuel to a preliminary purification treatment with sulfuric acid. This purification has been deemed necessary to remove from the oil certain constituents such as unsaturated hydrocarbons considered as undesirable in a motor fuel. In carrying out this purification treatment it is necessary to agitate the oil thoroughly with sulfuric acid, separate the resultant acid sludge, and then neutralize the oil by treatment with caustic. The cost of the acid, caustic, agitators, etc. represents a substantial part of the total outlay necessary in the production of a motor fuel and under some conditions such as those prevailing in small plants where a relatively limited quantity of crude light oil is produced, the expense incident to such purification operations renders the process of refining the light oil into motor fuel commercially prohibitive.

The principal object of this invention is the production directly from crude coke oven light oil of a fractional distillate which is suitable for use as a motor fuel without further treatment and the production of this product by a process of distillation which is not preceded or followed by an acid wash treatment. The elimination of this acid-wash step is an advantage which renders the invention especially useful in plants having a relatively small output of light oil.

According to my invention, crude coke oven light oil without any preliminary purification by washing with sulfuric acid is charged directly into a suitable distilling vessel and then heated until a low boiling fraction containing the low boiling constituents of the crude oil undesirable in a motor fuel is vaporized and separately collected and con-

densed. I have found that by slowly distilling off a low boiling fraction amounting to about 10-15% by volume of the crude oil the low boiling impurities of the crude oil objectionable in a motor fuel, including sulfur impurities removable by a distillation operation, may be satisfactorily removed therefrom to such an extent as to render purifying the motor fuel fraction with sulfuric acid unnecessary. After the separation of this low boiling distillate, the heating of the oil charge is continued and a distillate produced having characteristics which adapt it for use as a motor fuel without further purification. In the production of this fraction, the rate of distillation is preferably regulated so that only small quantities of toluol are present in the distillate, the toluol content of the total distillate in general, being not in excess of about 2% and the dry or end point of the distillate, ordinarily, being about 95-100° C. Heating of the oil charge is then preferably continued until a sample of the residue when tested has a first drop point of about 160° C. The fraction obtained by this distillation is preferably combined with the low boiling fraction initially obtained and the resultant product may be marketed as such or purified by treatment with sulfuric acid in the usual manner and separated into pure products by distillation. The amount of sulfuric acid needed for the purification of these combined fractions is much less than that required for the purification of a corresponding amount of crude oil. The distillation residue may be disposed of as coal tar oil.

Referring to the accompanying drawing which illustrates diagrammatically a suitable form of apparatus for practising the invention, a still 1 is provided having a conduit 2 for the introduction of crude oil thereto and equipped with both indirect heating means, steam coil 3, and direct heating means, steam pipe 4, having apertures therein for the introduction of steam into the distillation mass. Extending from the still is a stand pipe 5 and connected in parallel therewith is a suitable form of distilling column 6 equipped with any usual form of distillation rings or plates. Valves 8, 9 and 10 di-

50 55 60 65 70 75 80 85 90 95 100

rect the vapors evolved from the still through the column 6 or directly upward through the stand pipe 5, depending upon their position. The upper end of the distilling column 6 is preferably provided with a water cooled reflux condenser 7 of a conventional type for controlling the rate of distillation. Stand pipe 5 leads to condenser 11 which is connected to a separatory vessel 12 for separating any water present in the condensate. Connected to the separatory vessel are two tanks 13 for separately collecting the various fractional condensates.

The method of operating the apparatus will be apparent from the foregoing and the following illustrative example of the application of the invention to a crude coke oven light oil having a "combined benzol" content, i. e. benzene, toluol, etc., of about 79%.

Approximately 8000 gallons of this crude oil are charged into the still 1 and distillation initiated by passage of steam through coil 3. Valve 8 is closed and valves 9 and 10 are open so that the evolved vapors pass into distilling column 6. Vapors are withdrawn from the top of reflux condenser 7 through pipes 9 and 5 and condensed in condenser 11 and the condensate collected in one of the collecting tanks 13. The distillation should be carried out at a slow rate so that substantially all of the low boiling constituents undesirable in a motor fuel and relatively free from the desired motor fuel fraction are distilled off as for example about 150 gallons or about 2% per hour, control of the rate of distillation being had by adjustment of reflux condenser 7 and steam coil 3. The rate of distillation may be varied somewhat according to the character of the crude oil, the quality of the motor fuel desired, and similar conditions. However, the optimum rate for any given set of conditions may be readily ascertained by submitting the product, particularly the subsequently formed motor fuel fraction, to the usual tests. The distillation is continued until the distillate tests about 78° C. (first drop) and its volume amounts to about 925 gallons, i. e., an amount equivalent to about 12% of the oil charged. The separation of a low boiling fraction having a volume of about 10-15% at a suitable rate of distillation as indicated, ordinarily suffices to remove from the crude oil substantially all of its low boiling constituents undesirable in a motor fuel.

After the separation of the low boiling fraction, heating of the crude oil in still 1 is continued and distillation carried on as before through distilling column 6 to produce the motor fuel fraction. This fraction is likewise distilled slowly and preferably at such a rate that the distillate contains not more than about 2% toluol, and the distillation continued until the resulting distillate has a volume of about 40-50% based upon

the volume of crude oil charged, e. g., about 3800 gallons, and an end or dry point corresponding to that of the desired motor fuel, for example, about 95-100° C. This fraction is likewise condensed in condenser 11 but is separately collected and disposed of directly as motor fuel as no purification by treatment with sulfuric acid is necessary to adapt it for use for this purpose.

The motor fuel provided by this invention may be distinguished from the heretofore known types of motor fuel derived from coke oven light oil since the absence of any treatment with sulfuric acid in its production imparts certain distinguishing characteristics thereto. For instance, the motor fuel produced according to my invention has an acid wash color above normal, being above 14 on the standard test scale known as "Barrett Colorimetric Scale", (cf. Journal of Industrial and Engineering Chemistry for 1918, page 1006) while other motor fuels also produced from crude coke oven light oil but by a process involving their purification with sulfuric acid have an acid wash color below 12.

While my process satisfactorily removes low boiling impurities which are undesirable in a motor fuel, for example giving rise to a discolored product on standing, it does not remove all the unsaturated hydrocarbons as is the case when the acid purification treatment hereinabove referred to is used. Authorities now hold that certain of these unsaturated bodies of the olefine type are not only not undesirable in a motor fuel but are beneficial in that they impart "anti-knock" properties to the fuel. Accordingly not only does my process remove undesirable materials for which it has been necessary heretofore to use the expensive acid treatment, but materials heretofore removed by such treatment and which are not only noninjurious but beneficial, are caused to remain, thereby giving a new and improved motor benzol fuel.

After the separation of the motor fuel fraction valves 9 and 10 are closed and valve 8 opened so that the vapors pass directly through stand pipe 5 over into condenser 11 and distillation of the crude oil is continued preferably with the use of direct steam supplied through pipe 4. Water present in the condensate is separated in the separatory vessel 12, and the distillation continued until a sample of the residue remaining in still 1 has a first drop point of about 160° C. and the total fraction from this distillation has a volume of about 30-40% of the crude oil charged, for example, about 2300 gallons. This fraction comprises practically all the toluol content of the crude oil, and the high boiling constituents commonly designated as the "solvent" fraction. This toluol-solvent fraction is preferably combined with the low boiling fraction initially obtained giving a

resultant product which may be readily marketed as such. The distillation residue, amounting to about 10% of the crude oil charged is disposed of as coal tar oil.

5 The crude oil is accordingly converted into motor fuel, and other useful fractions, directly by distillation without any sulfuric acid purification treatment with its attendant difficulties and expense. In utilizing the combined fractions for the production of pure products by the separation of the constituents thereof, purification of these fractions with sulfuric acid may be resorted to, in which instance it has been found that the acid required is much less than that required according to the usual practice of submitting all the crude oil to the acid treatment and then distilling for the production of the motor fuel and other fractions.

20 By the term "crude coke oven light oil", used in the claims, is meant light oil which has not been washed with sulphuric acid or otherwise purified.

What is claimed is:

25 1. The process of producing motor fuel from crude coke oven light oil which comprises slowly distilling the crude oil whereby to separate a low boiling fraction having a volume of about 10-15% based upon the crude oil and containing low boiling constituents undesirable in a motor fuel, condensing and separately collecting said low boiling fraction, further slowly distilling the crude oil and separately collecting the distillate until 30 it has a volume of about 40-50% based upon the crude oil, whereby a fractional distillate is produced suitable for utilization as a motor fuel without further purification.

2. The process of producing motor fuel from crude coke oven light oil which comprises slowly distilling crude oil whereby to separate a low-boiling fraction having a volume of about 10 to 15 per cent based upon the crude oil and containing low-boiling constituents undesirable in a motor fuel, condensing and separately collecting said low boiling fraction, further slowly distilling the crude oil and separately collecting the distillate until 45 small quantities of toluol occur therein whereby a fractional distillate is produced containing not more than about 2 per cent of toluol and suitable for utilization as a motor fuel without further purification, continuing the distillation to separate a toluol fraction, and condensing and combining said toluol fraction with the low-boiling fraction initially produced.

In witness whereof I hereto set my hand.
JOSEPH J. LAWTON.
